(57) **CLAIM**

The ornamental design for a grille surround, as shown and described.

DESCRIPTION

FIG. 1 is a perspective view of a grille surround according to our new design;

FIG. 2 is a front elevational view of the grille surround of FIG. 1;

FIG. 3 is a top plan view of the grille surround of FIG. 1; and, FIG. 4 is a left side elevational view of the grille surround of FIG. 1.

The rear of the grille surround is unornamented.

The broken lines shown in the drawings illustrate portions of the grille surround that form no part of the claimed design.

1 Claim, 3 Drawing Sheets
